UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

CASTING AND FINISHING MACHINE FOR CURVED STEREOTYPE PRINTING PLATES.

Application filed April 17, 1923, Serial No. 632,639. Renewed December 27, 1926.

This invention relates to a machine for casting and finishing curved stereotype printing plates.

The principal objects of the invention are to provide mechanism for both casting and finishing the plates of such a nature as to reduce the expense of the plant, and avoid the expense of providing any means for conveying the plate from one place to another for finishing it; to provide for finishing the plates in the casting mold without providing any separate finishing machine; to provide for ejecting the matrix before the finishing is performed so that the plate can be brought back to rest against a solid metal surface during the finishing operation; to provide means whereby, after the matrix is ejected, the plate will be forced back the proper distance in the mold so as to seat firmly against the back, whereby the latter will form a firm backing for the plate during the shaving operation; to provide means whereby the core is rotated two complete revolutions after each casting is made to perform all its operations, first to eject the matrix, second to restore the cast plate to its original position in the casting box, third, to force the cast plate back to occupy the space left by the ejection of the matrix, fourth to shave the back of the plate, and fifth to eject the plate; to provide improved means for holding and releasing the curved ends of the matrix and cast bevels upon the plate; and to provide automatic means for releasing the matrix bar at the proper time to permit the ejection of the matrix with the cast plate, and thereafter bringing it back and locking it to prevent the ejection of the cast plate when the core is turned further to shave the plate. Additional objects and advantages of the invention will appear hereinafter.

Reference is to be had to the accompanying drawings, in which—

Fig. 1 is a plan of a casting and finishing machine constructed in accordance with this invention;

Fig. 2 is a side view of the same as indicated by the arrow 2 in Fig. 1;

Fig. 3 is an end view showing the clutch mechanism, as indicated by the arrow 3 in Fig. 1;

Fig. 4 is a side view of the same showing the trimming saw mechanism, see arrow 4 in Fig. 1;

Fig. 5 is an end view of the mold, as indicated by the arrow 5 in Fig. 1;

Fig. 6 is a sectional view on the line 6—6 of Fig. 5 through the core and cast plate, showing the parts in the position in which they stop;

Fig. 7 is a sectional view, as indicated by the line 7—7 in Fig. 6;

Fig. 8 is a fragmentary end view of the mold showing the mechanism for controlling the matrix bar, see arrow 8 in Fig. 1; this shows the end opposite that shown in Fig. 3;

Fig. 9 is a transverse sectional view through the interior of the mold illustrating the mechanism below for operating the pouring funnel;

Fig. 10 is a similar view with some features omitted showing the pouring funnel in open position and the trimming saw in action;

Fig. 11 is a view similar to Fig. 10 but showing the operation of stripping the matrix from the plate, the core rotating through its first half revolution;

Fig. 12 is a similar view showing the parts in the position they assume when the core has made a complete revolution and started on its second with the operation of shaving just started;

Fig. 13 is a similar view showing the plate partly ejected on the second half of the second revolution of the core; and

Figs. 14 and 15 are enlarged sectional views of the mold with the cast in position, the latter showing its manipulation after the matrix is removed.

This machine is designed to reduce the expense and complication of the machinery for casting and finishing curved stereotype plates for use particularly in small plants, and yet be capable of use in many large plants with much saving in the original cost of the machinery and space occupied thereby.

As will appear, the operator can insert the matrix, close the mold by hand, and then introduce the metal at the proper time. After the casting has been sufficiently cooled he has to open the mold by raising the riser forming funnel. Then he operates the

mechanism by hand for trimming off the riser. The funnel is closed again later by mechanism controlled by the foot of the operator. The operator starts the core turning mechanism into operation by hand for ejecting the plate and matrix during a half revolution of the core. The matrix is stripped from the core by hand as it emerges from the back on the core. The next half revolution restores the plate back to its original position in the mold, but not backed by the matrix. The plate is shifted relative to the core to compensate for the space left by removing the matrix before shaving. The rotation of the core continues and during the first half of its second revolution a blade on it shaves out the plate. During the fourth half revolution the plate is ejected. The operator then has to insert the matrix in the mold again for the next cast. The matrix bar is locked and unlocked automatically at the proper times.

I have shown the mechanism as mounted on a frame 9 provided with a power driven shaft 10 rotating constantly. This shaft is provided with a rotating clutch section 11 slidably keyed to it and adapted to be moved by a hand clutch lever 12 into position to clutch it to a worm 13 rotatably and freely mounted on the shaft 10. This worm operates a worm wheel 14 fixed on a shaft 20 and causes it to rotate two complete revolutions when the lever is moved automatically to draw the clutch 11 out and stop the machine. This clutch lever has a roll 15 which rotates on a cam 16 fixed on the worm wheel. This cam has a depression 17 for receiving the roll 15 at the end of each rotation and permitting the stopping of the wheel 14 in the manner to be described.

The clutch lever 12 is slidably keyed on a shaft 18 which has a fixed arm connected with a pivoted spring rod 19 for holding the shaft and connected parts in either extreme position. The arms for supporting the roll 15 and the clutch roll or stud are also fixed to this shaft 18. A clutch throw-out arm 8 on the clutch lever 12 has a projecting end adapted to engage in a square screw thread 7 on the shaft 20 when the lever 12 is thrown in. The screw moves this arm and the lever 12 along the shaft as the latter rotates. Just before the end of two complete revolutions a stop projection 6 at the end of the thread engages the end of the arm 8 and forces it back at the second time when the depression 17 registers with the roll 15. This turns the shaft 18 and throws out the clutch, thus stopping the shaft 20 when it has completed exactly two revolutions. A spring 5 on the shaft 18 forces the starting clutch lever 12 and clutch throw-out arm 8 to slide back along the shaft after the arm 8 is disconnected from the screw thread 7.

This leaves the clutch lever in position ready to be turned to start the machine.

The shaft 20 is mounted on the fixed frame 10 which is provided with a stationary concave back 21 for receiving a matrix M against which the metal is to be cast to form the printing plate. The other side of the mold is formed by a convex core 22 fixed on the shaft 20 and rotating with it. The back and core are provided with cavities 23 which are supplied with cooling water in ways well known in this art.

The semi-cylindrical mold formed by these two parts is completed on one straight edge by a matrix bar 25 pivoted on a longitudinal hinge shaft 26. This matrix bar has a slot or notch 27 for the edge of the matrix. The ends of the matrix are held by engagement with two bevel rings 37 in the ends of the mold or back 21. The shaft 26 is mounted to turn in bearings in brackets 27a carried at the side of the back and is provided with a spring 28 for yieldingly holding the matrix bar up in open position away from the edge of the box. The shaft 26 is operated by a handle 24 thereon.

Over this shaft 26 is a core groove seal hinge 29 having a spring 30 surrounding it and also surrounding a pin 31 on a projection 32 movable with the matrix bar 25. This spring presses down on a core groove seal 33 which is pivoted on a hinge 29. This is shaped to cover the matrix bar and seal that edge of the mold. It is forced down by the spring 30 independently of the other spring 28 and tends to keep the seal 33 in closed position against the bar 25 as shown in Figs. 9 and 10 but allows it to yield as indicated in Fig. 12.

The core end or bevel rings 37 hold the curved edges of the matrix and cast opposite bevels on the plate. They are moved laterally to clear the plate P when that is to be moved in the mold for stripping the matrix or moving the plate back in the mold ready for shaving. These rings are held in place by a spring 38 bearing against a collar 39 pinned to a rod 40 and against a fixed lug 36. This link and two similar links 42 are pivoted to a crank plate 41 at different points around it. These links 42 have the same motion but move in opposite directions to operate two levers 43 pivoted to the bevel rings 37. These rings therefore are held in casting position by the spring. They are drawn away once at the start of each revolution of the shaft 20 by a cam 44 on that shaft operating a lever 45 connected with the rod 40 and held back until the end of the revolution. So they do not resist the turning of the plate to eject the matrix or deliver it or prevent the thrusting back of the plate in the mold for shaving.

On the starting clutch lever 12 there is a

projection 69 having a pin 70. When this clutch lever is moved over to the starting position this pin will engage a stud or roll on an arm 71 on a shaft 72 running across the machine and turn the shaft. On this shaft are two cams 73 located in position to engage and move the pair of levers 74 mounted at opposite ends of the machine and release the hooks 75 which normally hold projections 76 on the opposite ends of the matrix bar 25. This releases the matrix bar and the spring 28 swings it back out of the way. The edges of the projections and hooks are slanted so that when they are brought together they will easily slide over each other and the hooks will engage behind the projections. A pair of springs 77 are connected with the levers for yieldingly forcing the hooks into a position to close against and hold the matrix bar 25 closed.

Also mounted on the core are two arms 78 adapted to engage projections 79 on the two levers 74. Every time the core completes the first half of a revolution these projections will force the levers 74 back against their springs and release the matrix bar, if it is in closed position.

The core 22 is provided with a projection 61 and a shaving blade 62 extending across the core. It is also provided with a projection 80 adapted to be imbedded in the cast plate and to take the plate with the core as the core turns, provided the matrix bar is released. If, however, the matrix bar is prevented from being released this projection or tooth will plow its way out of the plate P. The core is also provided with a plurality of grooves or flats 81. I have shown three of them located at different distances apart circumferentially. These are made of a depth substantially equal to the thickness of the matrix. Of course they provide corresponding flats on the inside of the cast plate and these flats will rest against the convex surface of the core as the core rotates during the shaving operation. They are provided for the purpose of pushing the cast plate out from the core a distance equal to the thickness of the matrix to seat the cast plate firmly against the back after the matrix is removed to permit of holding the plate in the box and shaving its interior. The core also has square shouldered circumferential grooves 82 to ensure the rotation of the plate with the core.

The pouring funnel 35 is mounted to swing on a shaft having an arm connected with a rod 64 for turning the shaft and swinging the funnel. A spring 65 normally holds the rod down and the funnel up. A treadle 66 is connected to the rod for elevating it. The length of the rod is adjustable by a turn buckle or the like. The treadle is held down by a snap-hook 67.

For the purpose of sawing off the riser as will appear, there is an operating handle 47 on a shaft 48 carried under the back by the frame. On this shaft 48 there is a gear or other driving wheel 46 which can be turned from either extreme position to the other. It is left in either position so that at the next operation it can be turned back through the same arc but in the opposite direction. This has the same effect in both cases, that is, it oscillates the wheel 46. This wheel has cogs on it which mesh with the links of a chain 49. The chain is movable over guides 50 at its ends. At each oscillation of the wheel 46 a saw carriage 51 connected with the chain moves through a straight path equal in length to the linear motion of any point on the wheel while it makes an oscillation in one direction. This carriage 51 is in the form of a slide moving horizontally, on inclined ways 52 on the side of the back 21.

This carriage 51 carries three parallel inclined shafts, a saw shaft 53 and two idler pulley shafts 54. On each of the latter there is a pulley 55. A belt 46 runs over these pulleys and also over a pulley on the saw shaft 53. This belt 56 is driven from a pulley 57 on a shaft 58 constantly geared by gears 59 to the main driving shaft 10 so that this belt runs constantly in the same direction. On the saw shaft 53 is a saw 60.

This is a tail cutting saw which, as it moves from one side to the other in either direction, constantly rotating, severs the riser from the plate. The parts are so timed by the operator that the saw passes into the plate just after the funnel 35 has been raised and when it emerges from the plate the funnel is restored to its closed position. The parts are then stopped there but the saw continues to rotate and it has no further action until the handle 47 is moved back again. Then, moving in the opposite direction, it saws off another riser. It will be seen therefore that this trimming mechanism is mounted on the casting box and operates on a cast plate while the latter is in the mold in which it was cast.

Operation.

With the mold and core in the position shown in Figs. 9 and 10, the mold being empty, the matrix bar 25 raised and the pouring funnel 35 closed down, the matrix 120 is inserted from the left hand side edgeways. Its edges that are to be curved enter under and are guided by the pair of bevel rings 37. It is pushed along under these rings until its forward edge enters the notch or 125 slot 36 provided for it in the funnel 35 and then it is let back against the back and fits snugly against it. The bar 25 holds it at that side after this bar is forced down against it by the handle 24. The matrix is 130

now held snugly at all four edges. This makes the mold ready to receive the molten metal through the spout 90. As soon as the casting cools sufficiently, which is assisted by the circulation of water through the core and back, the operator releases the treadle 66 by pressing his toe against the snap-hook 67. This raises the pouring funnel 35 to the position shown in dotted lines 10 in Fig. 9. Now the operator turns the lever or handle 47 around 180° in either direction which moves the saw along the edge of the plate. The saw being rotated constantly it saws off the riser which is removed 15 and then the plate is ready for stripping and shaving. The operator also lowers the funnel.

The operator starts the machine by moving the starting clutch lever 12 from the position shown in full lines in Fig. 3 to the position indicated in dotted lines. This throws in the clutch and starts the shaft 20 to rotate taking with it the core. The movement of the clutch lever from one position 25 to the other swings the lever 71 from the position shown in Fig. 8 and moves the two levers 74 in at the bottom so as to release the matrix bar from the hooks 75. Then the spring 28 is free to raise the matrix 30 bar. It will be understood that the bevel rings are moved outwardly first during each revolution at the beginning of the complete revolution by the cam 44. These actions release the plate so that it can be ejected. 35

The rotation of the core, provided as it is with the flats 81 and the pins or projections 80 and the square shouldered grooves 82, will necessarily take the plate with it and 40 also the matrix. Therefore the effect of this action is to move the parts from the position shown in Fig. 10 to that shown in Fig. 11. As the plate and matrix move out of the mold the operator strips the matrix from the plate as indicated in that figure. The spring 5 moves the parts 12, 8 and 69 along the shaft, releasing the levers 74. 45

The core continues to rotate and, as it reaches the end of its first half revolution, 50 the projections 78 engage the projections 79 and hold the hooks 75 back, but that performs no function at that time. But as soon as they pass, the springs 77 force the levers over into locking position. The operator at 55 this time forces the matrix bar back into its proper position and it is locked automatically by the hooks. The second half of the first rotation of the core brings the plate around, with the matrix stripped off, back into the mold. When its forward end engages the matrix bar it is prevented from moving any 60 farther on account of the fact that this bar is locked by the hooks 75. The core, however, continues to rotate, the end rings draw back, 65 and the pins 80 plow out of the plate. It is

then again in a position similar to that shown in Fig. 10 except that the plate has been rotated a complete revolution back to the starting point. The first action of the rotation of the core beyond this exact point 70 is to force the plate out in the mold from the position shown in Fig. 14 to that shown in Fig. 15. Prior to this there was a space beyond the plate P between it and the back which the matrix M had previously occupied 75 but now the plate is pushed out and fully occupies that space. There is a space behind it caused by the flats on the plate engaging the circular parts of the core. Therefore the cast is held in fixed position 80 and the shaving blade now comes into engagement with it during half a revolution and shaves it. As the core reaches the end of this half revolution the projections 78 again engage the projections 79 and unlock 85 the matrix bar, which then yields. The core continues to rotate through the fourth half revolution and the pins 80 come around into engagement with the rear end of the plate as indicated in Fig. 13 and push the plate 90 out. When it is substantially ejected by this action the operator takes it off the core and puts it to one side. This completes one cycle of operations.

It will be seen therefore that although this machine requires more attention on the part of the operator than a full automatic machine it involves a very much less expensive plant. It adds very little to the cost of the simplest form of casting machine and yet 95 provides for casting, ejecting the plate and matrix, and finishing. The cost of the machine is very greatly reduced and also the cost of the up-keep. By casting the plate and shaving it in the same chamber I not 100 only reduce the amount of mechanism employed but I avoid the necessity of handling the plate with the possibility of damaging it. I provide for backing up the plate by forcing it positively back into the mold in which it 105 was cast to provide a solid metal seat to sustain the pressure applied to the plate during the shaving operation. The ejection of the plate and matrix is performed also without providing any additional mechanism except 110 the pins on the core and the means for releasing the matrix bar and end rings. This invention also involves a new method consisting in shaving the plate in the mold in which it is cast while the plate is in stationary condition backed up against the surface on which it is cast. 115

I do not specifically claim herein any mechanism shown and claimed in my co-pending application with the same title filed April 14, 1923, Serial No. 632,638. 125

Although I have illustrated and described only a single form of the invention I am aware of the fact that modifications can be made therein by any person skilled in the art 130

without departing from the scope of the invention as expressed in the claims. Therefore I do not wish to be limited to all the details of construction herein shown and described but what I do claim is:—

1. The combination with a stereotype plate casting back, of a core rotatable therein, means for starting the core to rotate, and means for automatically stopping the core 10 when it has completed two full revolutions.

2. The combination with a stereotype plate casting back, of a core rotatable therein, means for starting the core to rotate, means for automatically stopping the core 15 when it has completed two full revolutions, and means rotatable with the core for shaving the interior of the plate in the back as the core rotates during its second revolution.

3. The combination with a stereotype 20 plate casting mold of semi-circular shape having its axis horizontal, of a core cooperating with the back to complete the mold cavity and rotatable on the axis of the back, said core being provided with means for taking the plate with it as it rotates a full 25 revolution, and means whereby the continued rotation of the core through another half revolution will shave the back of the plate.

4. The combination with a stereotype 30 plate casting back of segmental form, of a core having a convex surface rotatable therein between which and the back the plate is adapted to be cast, means rotatable with the core for shaving the interior of the plate in 35 the back as the core rotates through the third half revolution, hand operated means for starting the rotation of the core, and automatic means for stopping it after it has completed two revolutions.

40 5. The combination with a stereotype plate casting mold of semi-circular shape, of a core cooperating with the back to complete the mold cavity and rotatable on the axis of the back, means for taking the plate 45 with the core and restoring it to position in the back as the core rotates through one revolution, and means on the core for shaving the interior of the plate as the core rotates through its second revolution.

50 6. The combination with a semi-cylindrical back and a semi-cylindrical core rotatable on the axis of the back, said core having a shaving blade fixed thereon for shaving the interior of the cast plate in the back, said 55 core also having near its forward edge a projection adapted to carry the casting with it when the core is rotated in the absence of resistance, means for preventing the rotation of the plate during the second rotation 60 of the core, thus causing the projection to pull out of the plate and to come into contact with the rear edge of the plate when the rotation is continued through another half revolution to enable the core to push 65 the plate out of the back by its rotation.

7. The combination with a stereotype plate casting back of segmental form, of a core having a convex surface rotatable therein between which and the back the plate is adapted to be cast, and means rotatable with the core for shaving the interior of the plate in the back after the core has rotated a full revolution and while it is going through a second revolution.

8. The combination with a stereotype 75 plate casting mold of semi-circular shape, of a core cooperating with the back to complete the mold cavity and rotatable on the axis of the back, means for rotating the core two revolutions and then stopping it automatically, and means whereby as the core rotates through the first half revolution the plate will be moved with it out of the back to expose the matrix thereon for stripping, 80 said core being provided with means for shaving the interior of the plate as it rotates through the next half revolution.

9. The combination with a segmental 85 plate casting back, of a core relatively rotatable therein, and means on the core for ejecting the matrix during a half revolution of the core and for holding the plate on the core as it continues to rotate and restoring the plate to the mold.

10. The combination with a stereotype 90 plate casting back of segmental form, of a core having a convex surface rotatable therein, means for ejecting the matrix, and means rotatable with the core for shaving the interior of the plate while the plate rests 95 against the back substantially in its original casting position therein.

11. The combination with a stereotype 100 plate casting back of segmental form, of a core having a convex surface rotatable therein, means rotatable with the core for ejecting the matrix as the core rotates a half revolution, and means whereby the continued rotation of the core through another 105 part of a revolution will shave the plate in 110 the back.

12. In a stereotype plate casting and finishing device, the combination with a curved back, and a core relatively rotatable therein, 115 of a matrix bar on the edge of the back, means for locking the matrix bar in closed position, yielding means for holding the locking means adapted to yield to unlock the bar and permit the plate to be ejected, 120 and means for automatically unlocking the locking means when the core starts to rotate.

13. In a stereotype plate casting and finishing device, the combination with a curved back, and a core relatively rotatable therein, 125 of a matrix bar on the edge of the back, means for locking the matrix bar in closed position, yielding means for holding the locking means adapted to yield to unlock the bar and permit the plate to be ejected at the middle of each revolution of the core, 130

- a core starting lever, and means operated by said lever for unlocking the locking means when the lever is moved to start the core into rotation.
14. The combination with a stereotype plate casting mold having a rotatable core and a movable matrix bar, of a clutch adapted to connect the core with a source of power, a clutch lever for operating the clutch, and means operated by the clutch lever for releasing the matrix bar when the clutch lever is moved to close the clutch.
15. The combination with a stereotype plate casting mold having a rotatable core and a movable matrix bar, a spring for normally moving the matrix bar to open position, a locking device for the matrix bar, and yielding means for holding the locking means in operative position, of a clutch adapted to connect the core with a source of power, a clutch lever for operating the clutch, and means operated by the clutch lever for releasing the matrix bar locking means when the clutch lever is moved to close the clutch to permit ejection of the plate by the rotation of the core.
16. In a stereotype plate casting and finishing device, the combination with a curved back and a concentric core rotatably mounted with respect thereto, of a pouring funnel mounted along one edge of the back, a foot treadle, means for connecting said treadle with said pouring funnel for moving the pouring funnel into and out of operative position, and yielding means for holding the funnel back out of operative position.
17. In a stereotype plate casting and finishing device, the combination with a curved back and a concentric core relatively rotatably mounted with respect thereto, of a pouring funnel mounted along one edge of the back, a foot treadle, means for connecting said treadle with said pouring funnel for moving the pouring funnel into and out of operative position, yielding means for normally holding the pouring funnel back away from the mold, and positive means for holding it in operative position.
18. In a stereotype plate casting and finishing device, the combination with a curved back and a concentric core rotatably mounted with respect thereto, of a pouring funnel mounted along one edge of the back, a treadle, means connecting said pouring funnel with said treadle for moving the pouring funnel into and out of operative position, a matrix bar for closing the end of the mold, a pair of hooks for holding the matrix bar in its fixed position, and means for releasing said hooks.
19. In a stereotype plate casting and finishing device, the combination with a curved back and a concentric core rotatably mounted with respect thereto, of a pouring funnel mounted along one edge of the back, a treadle, means connecting said pouring funnel with said treadle for moving the pouring funnel into and out of operative position, a matrix bar for closing the end of the mold, a pair of hooks for holding the matrix bar in its fixed position, and means for releasing said hooks.
20. In a stereotype plate casting machine, the combination with the casting back, core, and a rotatable shaft on which the core is mounted, of a pair of end rings, and means on the shaft for moving said end rings outwardly once during each rotation of the core for releasing the cast plate.
21. The combination with a stereotype plate casting back of segmental form, of a core having a convex surface rotatable therein, means for removing the matrix, means rotatable with the core for shaving the interior of the plate while the plate rests against the back substantially in its original casting position therein, said core having means for pushing the plate radially against the back and holding it there during the shaving operation.
22. The combination with a segmental concave casting back for stereotype plates, of a convex core therefor having a series of depressions each extending only part way around its convex casting surface and having a depth substantially equal to the thickness of the matrix from which the plate is cast for the purpose described.
23. The combination with a segmental concave casting back for stereotype plates, of a convex core therefor having a series of shallow depressions arranged at a plurality of points around its convex casting surface having a depth substantially equal to the thickness of the matrix from which the plate is cast.
24. The combination with a stereotype plate casting back and means for shaving the interior of a plate in the back, of a core rotatable in the back having means for pushing the plate radially against the back and holding it there during the shaving operation.
25. In a stereotype plate casting mold, the combination of a relatively movable back and core, with means for moving the cast plate out of the back and thereafter restoring the plate to a position within the back.
26. The combination with a stereotype plate casting mold having a relatively movable back and core, of means whereby the cast plate is removed from the back by said relative motion and thereafter restored to its position in the back by the continuation of that motion.
27. The combination with a segmental plate casting mold having a concave back and a rotatable convex core, of means for starting the core to rotate, means for stop-

- ping the core when it has completed two full revolutions, means for allowing the plate to rotate with the core during the entire first revolution, and means for preventing the rotation of the plate with the core during the first half of the second revolution and permitting it to be ejected by the core during the second half of its second revolution.
- 10 28. A convex core for a stereotype plate casting mold having a series of depressions on its convex surface unequally spaced apart around it circumferentially for the purpose described.
- 15 29. A convex core for a stereotype plate casting mold having a series of flats on its convex surface and provided with a circumferential square groove to hold the plate firmly on the core when outside the back.
- 20 30. A convex core for a stereotype plate casting mold having a circumferential square groove to hold the plate firmly on the core when outside the back.
- 25 31. A convex core for a stereotype plate casting mold having a circumferential square groove to hold the plate firmly on the core when outside the back and having a pin projecting therefrom adapted to be embedded in the cast plate.
- 30 32. A convex core for a stereotype plate casting mold having a blade thereon for shaving the interior of the casting.
- 35 33. A semi-cylindrical and rotatable core for a stereotype plate casting mold having at a point adjacent to one flat surface a radial blade located in position to shave the interior of a concave plate as the core rotates through a half revolution with the plate in the mold.
- 40 34. A core for a stereotype plate casting mold having a curved casting surface and a substantial radially disposed shaving blade carried by the core.
35. The method of casting and finishing curved stereotype printing plates which 45 consists in casting a plate in the mold and then shaving the concave surface of the plate while it is in the mold.
36. The method of finishing a curved stereotype printing plate which consists in 50 shaving its interior while the plate rests in the back of the mold.
37. The method of casting and finishing curved stereotype printing plates which 55 consists in casting the plate in a curved back against a matrix therein, then removing the plate and matrix simultaneously in a circular path, stripping the matrix from the plate, and returning the plate to the back to be shaved therein.
38. The method of finishing and delivering a cast stereotype printing plate which 60 consists in exerting a pressure on the edge of the plate in the mold in a circular direction and ejecting the plate and matrix together from the mold by a circular motion, keeping the plate and matrix in contact as they emerge from the back, stripping the matrix from the plate, continuing the circular motion to restore the plate to its casting 65 position in the mold, moving the plate outwardly in the mold to seat it firmly against the back, and then shaving the back of the plate.
39. The method of finishing a cast printing plate which consists in pushing the plate and matrix out of the mold in a direction 70 parallel with the printing surface of the plate, stripping the matrix from the surface of the plate, restoring the plate to the mold, moving the plate in the mold a distance substantially equal to the thickness of the matrix, and shaving the back of the plate.
- In testimony whereof I have hereunto affixed my signature.

HENRY A. WISE WOOD.
